(57) **CLAIM**

The ornamental design for a fiber optic light cable, as shown and described.

DESCRIPTION

FIG. 1 is a top view of a fiber optic light cable according to the present invention.

FIG. 2 is a bottom view of the fiber optic light cable of FIG. 1. FIG. 3 is a front perspective view of the fiber optic light cable of FIG. 1.

FIG. 4 is a left perspective view of the fiber optic light cable of FIG. 1.

FIG. 5 is a right perspective view of the fiber optic light cable of FIG. 1.

FIG. 6 is a rear perspective view of the fiber optic light cable of FIG. 1; and,

FIG. 7 is a top perspective view of the fiber optic light cable of FIG. 1.

In the drawings, the broken lines are for the purpose of illustrating environment only, depict unclaimed subject matter only and thus form no part of the claimed design.
